NONLIFTING INJECTOR

Hans Deutsch and Paul Jómek, Vienna, Austria,
assignors to the firm of Alex. Friedmann,
Vienna, Austria

Application March 19, 1934, Serial No. 716,405

4 Claims. (Cl. 103—271)

The invention relates to non-lifting injectors, especially of the type wherein the member controlling the water supply to the nozzles is operated automatically by a steam actuated member which controls the steam supply to the system of nozzles.

In order to obtain a starting of non-lifting injectors with a high degree of reliability, it is necessary to open first the water supply to the system of nozzles and to allow the admission of steam to the nozzles only after a sufficient amount of cold water has passed through the injector and has been discharged through the overflow valve into the open air. Thus the steam when entering, finds itself in presence of a sufficient quantity of cold water in the nozzles: wherefore it will immediately condense so that the injector is easily started. In this way, however, starting operation will cause the loss of a smaller or larger amount of water, the quantity depending on the skill of the operator.

To decrease said loss and to avoid the manipulation necessary for opening the water valve, the above mentioned type of injector is employed, wherein the latter is actuated by a piston-like member operated by the pressure of the steam supplied to the injector. This type—though of advantage from the above mentioned point of view—has however the drawback, that the full steam jet always enters into the system of nozzles simultaneously with or even by virtue of its greater velocity before the water, so that generally a sufficient quantity of cold water for obtaining condensation will not be present; it is therefore difficult to start the injector and it is not possible to obtain an improved operation by opening the steam valve very slowly.

In order to obtain a sufficient but not excessive retardation of the admission of steam to the system of nozzles with respect to the admission of water it has been proposed to move the said piston-like member by the steam pressure against a weight or a spring, and to control the steam supply to the nozzles by this member in such a way that steam is admitted to its full extent only after a certain amount of lifting of the water valve. This arrangement is, however, unsatisfactory as the weight or the spring tension must of necessity be small in order to enable the starting of the injector even at low boiler pressures. Beyond a certain boiler pressure therefore the weight or the spring will not cause a sufficient retardation of the steam supply.

It is therefore the main object of this invention to provide an arrangement by which the retardation of the admission of the steam supply relatively to the admission of the water supply is obtained even in cases where the admission pressure of the steam is relatively high, for instance above 150 pounds per square inch. With

this end in view, a steam operated member controlled by the pressure of the steam supplied to the injector is provided, which opens the water admission valve, when steam is fed to the injector and which controls the whole cross-section through which steam is flowing or part of it. Moreover a water brake mechanism retarding the opening movement of said member to such an extent that the full steam jet can enter into the nozzles only after a sufficient amount of cold water has passed through the injector, is arranged, which consists of a piston, capable of moving within a hollow cylinder and when so moved, discharging a quantity of water through a restricted cross-section serving as a throttling means.

In a preferred embodiment of the invention, the water chamber of the brake mechanism may be connected to a chamber in which substantially atmospheric pressure prevails, (such as the free air or the water admission chamber of the injector), said connection being controlled by a shut-off member, so that the brake mechanism may be rendered inoperative by opening said shut-off member. Whenever the steam pressure is relatively low and in particular is far below the above mentioned limit taken as an example of 150 pounds per square inch, the time required for the braking action will increase and a notable loss of water will occur. The above described means allows in such a case of eliminating the braking action by opening the shut-off member and to thus remove the inconvenience experienced in connection with such very low pressures.

It is moreover possible to combine the hand operated throttling member for the water supply and the said shut-off valve for rendering the brake mechanism inoperative in such a manner that when a relatively low admission pressure of steam is used and the water flow is accordingly throttled by said throttling member by hand, the brake mechanism is automatically made inoperative.

By the arrangement according to the invention the steam supply to the nozzles is very effectively retarded even when high admission pressures of steam are employed. On the other hand, by suitably adjusting the braking mechanism the amount of water lost at each starting operation can be reduced to the least possible extent.

In the accompanying drawing, an injector arranged according to the invention is illustrated by way of example. Fig. 1 is a longitudinal sectional view and Fig. 2 a transverse sectional view along the lines II—II of Fig. 1.

Referring to the drawing the casing 1 of the injector is provided with a steam nozzle 2, a combining nozzle 3 and a delivery nozzle (not illustrated). These three nozzles are surrounded by the overflow chamber 17 provided in the usual manner with an overflow valve (not illustrated).

4 is the steam inlet and 5 the water inlet. A differential piston with two portions 6 and 7 is movable within openings 13 and 29 of the casing 1 respectively. The chamber 25 below the lower portion 6 of the piston is in communication with the open air by means of the opening 30 which is controlled by a ball shaped valve 28 operating under the influence of the gravity. A longitudinal hole 26 is provided in said differential piston 6, 7, the upper end of which is laterally directed so as to connect the chamber 25 with the chamber 27.

A second piston 31 rests upon the upper end of the differential piston 6, 7, which is likewise movable within an opening of the casing and from which a rod 32 adapted to act upon the water valve 9 projects. The valve 9 is provided with an upstanding hollow piston 15 movable within a sleeve 16, which serves as a brake cylinder. Between the piston 15 and the sleeve 16 there is provided a small clearance space so dimensioned that when the water valve 9 is raised by the piston 31, 32 a certain resistance is opposed to this movement by the water discharged from the interior 14 of the brake cylinder through the ring shaped space between the piston 15 and the sleeve 16. The valve 9 is pressed down upon its seat 9 by gravity and by a weak coiled spring 11.

The sleeve 16 forms part of a cock 18 having on its upper side a stem 24 provided with a square plug 19 at its end. The stem 24 is movable within the cover 21 and is provided with a longitudinal hole 20, the upper end of which is laterally directed so as to communicate with a channel 22 in the cover 21 when the cock 18 or the stem 24 assumes a certain position to be described later. The channel 22 finds a continuation in channel 23 arranged within the casing 1 and opening into the water inlet 5. As will be seen from Fig. 2, the inner end of the channel 22 opens into a circular groove 33 which partly surrounds the periphery of the stem 24.

The operation of the device is the following:

When the admission pressure of steam is relatively high and the brake mechanism is operative, the steam entering at 4 into the injector raises the piston 6, 7 owing to the differential action of the same. The rod 32 strikes against the underside of the water valve 9 raising it from its seat 10, so that water can immediately flow to the space 12 and to the system of nozzles. The path through which steam admission occurs, however, is still shut, because the opening 13 is freed only after the performance of a piston movement along a certain distance x . This movement is held back or retarded since the discharge of water from the interior 14 of the brake cylinder 16 causes the generation of a resistance while passing through the narrow annular cross-section left between the brake cylinder 16 and the brake piston 15. Thus the path for the steam admission is opened only after the passage of a certain amount of cold water into the injector and its discharge into the open air through the overflow valve.

When the admission pressure of the steam is relatively low, the water supply is throttled by turning the cock 18 by means of a wrench applied to the square plug 19. As will be seen from Fig. 2, when the stem 24 is turned at least about an angle α the hole 20 comes into communication

with the groove 33, so that the chamber 14 is in communication with the water inlet 5 by means of the channels 22, 23, and thereby with a space in which substantially atmospheric pressure prevails. The water in the chamber 14 can now easily escape therefrom so that the brake mechanism is rendered inoperative. Obviously the channels 22 or 23 may also directly lead into the open air.

The valve 28 serves for discharging the steam and the condensate from the chamber 25 as soon as the pressure is relieved. Thus after the injector is stopped, the steam escapes into open air and the injector is prevented from being heated by the same.

What we claim is:

1. A non lifting injector, comprising a set of nozzles, a member controlling the water supply and a further member controlling the steam supply to said nozzles, the latter operated by the steam pressure and adapted to act upon the first named member, a hand operated throttling member for the water supply, means for obtaining a retardation of the opening of the member controlling the steam supply, comprising a water operated brake mechanism, forming part of said throttling member, a channel connecting the water chamber of said brake mechanism with a space where substantially atmospheric pressure prevails, and a shut-off member inserted into said channel.

2. A non lifting injector as set forth in claim 1, in which said shut-off member and said throttling member are operatively connected so as to be operable by hand in common.

3. A non lifting injector, comprising a set of nozzles, a member controlling the water supply and a further member controlling the steam supply to said nozzles, the latter operated by the pressure of the steam admitted thereto, and adapted to act upon said first named member, a hand operated turning throttling member for the water supply, a water operated brake mechanism retarding the opening movement of said controlling member for the water supply and forming part of said throttling member, a channel arranged in said throttling member adapted to connect the water chamber of said brake mechanism with a space where substantially atmospheric pressure prevails in some positions of said throttling member.

4. A non-lifting injector, comprising a set of nozzles, a member controlling the water supply and a further member controlling the steam supply to said nozzles, the latter operated by the pressure of the steam admitted thereto and adapted to act upon the first named member, a manually turnable throttling member for the water supply, a water operated brake mechanism retarding the opening movement of said controlling member for the water supply, and forming part of said throttling member, a channel arranged in said throttling member so as to close or to connect the water chamber of said brake mechanism with a space where substantially atmospheric pressure prevails, in accordance to the angular position of said throttling member respectively.
